UNITED STATES PATENT OFFICE.

CHARLES WILLBER AND THOMAS WILLBER, OF MANCHESTER, ENGLAND.

HAIR-COMB-CLEANING DEVICE.

Application filed November 2, 1927, Serial No. 230,588, and in Great Britain November 27, 1926.

This invention relates to hair combs and cleaning devices therefor.

The main object thereof is to provide a simple but efficient means of removing foreign matter from between the teeth of hair combs. Another object is to provide means for guarding or shielding the teeth of a hair comb when the latter is not in use.

We attain these objects by the means illustrated in the accompanying drawing and hereinafter claimed. In the drawings—

Figure 1 is a side elevation of a hair comb with cleaner.

Figure 2 is an end view in section on line 2—2 of Figure 1, but with the cleaner moved into a different position.

Figure 3 is a plan view in section on line 3—3 of Figure 1.

Figure 4 is a side elevation of another comb with another cleaner.

Figure 5 is an end view in section on line 5—5 of Figure 4.

Figure 6 is a plan view in section on line 6—6 of Figure 4.

Referring to the drawings, in the construction shown in Figures 1 to 3 we provide a comb 1 with open ended slots 2 extending from the rear extremity in the direction of the teeth 3 of the comb 1, and we provide cylindrical pivots 4 extending across the gaps or slots 2. The pivots 4 may be formed integral with the comb.

We furthermore provide a strip 5 having at its rear edge projections 6 bent to form open eyes adapted to be engaged by the pivots 4. The projections 6 are preferably of springy material so that the said eyes can be forced on to and off the pivots 4. Thus the strip 5 is detachably hinged to the comb 1.

We provide on the strip 5 a plurality of lateral projections or teeth 7 corresponding in shape and position with the gaps between the comb teeth 3. The projections or teeth 7, hereinafter termed the cleaning teeth, project laterally from that side of the strip 5 which is opposed to the side of the comb 1.

The cleaning teeth 7 are of such lateral width and shape as to exactly fill the gaps between comb teeth 3 along the length of the comb teeth 3 and across the thickness or width thereof.

In operation when it is desired to clean the comb teeth 3, the strip 5 is swung downwardly on its hinges 4, 6 and the cleaning

teeth 7 are thereby caused to enter the gaps between the teeth 3 in a lateral direction and by engaging the said gaps, to force the foreign matter out at the other side of the comb 1. Owing to the arcuate movement performed by the strip 5 and therefore by the cleaning teeth 7, the cleaning teeth 7 first enter the gaps at the roots of the teeth 3 and thereby not only tend to force the foreign matter downwards as well as laterally outwards, but also insure engagement between and separation of such comb teeth 3 as may have become crossed or displaced at their free ends.

The strip 5 and cleaning teeth 7 may remain in the last described position and thus serve to protect the teeth 3 of the comb against injury and, where the comb is placed in the pocket, to prevent the comb teeth 3 from catching the pocket and prevent the entrance of fluff or the like between the comb teeth 3. Thus the strip 5 and cleaning teeth 7 can be employed in lieu of and to serve the same purpose as a case or sheath.

The strip 5 is preferably extended slightly beyond the extremities of the comb teeth 3 so as to leave free a part thereof for the purpose of more conveniently swinging the strip 5 upwardly to disengage the cleaning teeth.

When it is desired to again use the comb 1 it is merely necessary to swing the strip 5 upwards until it is situated behind the comb, the comb teeth 3 being then entirely free for use.

The strip 5, teeth 7 and projections 6 may be formed integral with one another, or the projections 6 may be formed separate and be attached to the strip 5 by any suitable means, for example by rivets. Thus the strip 5 and cleaning teeth 7, and in some cases the projections 6 can be moulded of suitable material, and the cost of production be thereby kept low.

In order to assist the ready engagement of the cleaning teeth 7 with the gaps between the comb teeth 3, we may form one or more cleaning teeth 7 with a projecting or leading corner 8, Figures 1 and 2, so that it or they enter its or their gap or gaps between teeth 3 before the other cleaning teeth 7 and thereby form a guide or guides for the correct approach and entry of the said other cleaning teeth 7.

It will be appreciated that the strip may be permanently hinged to the comb and that

the hinges may be provided at the ends of the back portion of the comb instead of at the rear part of the said back portion.

In lieu of connecting the cleaner to the comb by hinges or the like, of which parts are provided on the comb itself, we may form the cleaner as a separate and entirely independent entity which can be used on any known or existing comb the teeth gaps of which coincide in spacing and size with the teeth of the cleaner.

Figures 4 to 6 show a construction of separate and independent cleaner, 9 being a comb of any ordinary or known form. The cleaner consists of a strip 10 provided with cleaning teeth 11 which are arranged to exactly fit the gaps between the comb teeth 12 when the cleaner is applied to the comb 9. The strip 10 extends beyond the lower extremities of the teeth 11 and 12 to facilitate removal of the cleaner from the comb.

In use the strip 10 and therefore also the cleaning teeth 11 are completely removed from the comb 9 when it is desired to use the comb 9. To clean the comb 9 the strip 10 is pressed against one side of the same to force the cleaning teeth 11 laterally into the gaps between the comb teeth 12 and thereby expel all foreign matter from the said gaps.

When the hair has been combed the cleaner may be placed thereon to protect the comb teeth 12 against injury and if the comb is a pocket comb or bag comb, to also protect the pocket or bag against injury by the comb teeth 12, and furthermore to prevent the entrance of foreign matter between the comb teeth 12 when not in use. Owing to the friction between the teeth 11 and 12, the cleaner remains sufficiently securely in position on the comb 9 without the provision of any other means of securement.

From the hereinbefore stated description it will be appreciated that our invention provides a simple but very efficient means of completely cleaning hair comb teeth, whether they be bent or not, which means also serves the dual purpose of also acting as a case or sheath for protection of the comb or of the pocket in which the comb is carried.

It is to be understood that our invention

is applicable to combs having teeth at both edges. Where the first described construction is applied to such combs, it is so modified that the pivotal connection of the cleaning device 5, 7 is situated at the centre of the comb and the cleaning device is modified by having another set of cleaning teeth 7 arranged on the other side of the strip 5, so that by turning the strip 5 in one direction, one set of cleaning teeth 7 clean the comb teeth at one edge of the comb, and by turning the strip 5 in the other direction, the second set of cleaning teeth 7 clean the comb teeth at the other edge of the comb.

We claim—

1. A hair comb cleaning device comprising a flat member having lateral teeth or projections of the same length, width and depth as the teeth gaps of the comb to be pushed into the gaps from the side of the comb and completely occupy and fill all parts of the said gaps simultaneously and thereby force all foreign matter from between the teeth in a lateral direction relative to the comb teeth, and completely exclude foreign matter from the gaps when the comb is not in use.

2. A hair comb cleaning device according to claim 1 wherein the said member can be completely removed from the comb laterally relative to the direction of the length of the teeth.

3. A hair comb cleaning device according to claim 1 wherein one or more of the lateral teeth or projections are provided with projecting or leading corners to assist in guiding the lateral teeth or projections into the teeth gaps.

4. A hair comb cleaning device consisting of a strip having at one side cleaning teeth adapted to engage and completely fill the teeth of a hair comb and to be inserted laterally into the said gaps, the said strip being extended beyond the extremities of the said teeth.

In testimony whereof, we have signed our names to this specification at Manchester in the county of Lancaster, England, this 24th day of October, 1927.

CHARLES WILLBER.
THOMAS WILLBER.
